(57) **CLAIM**

The ornamental design for a display screen with graphical user interface, as shown and described.

DESCRIPTION

FIG. 1 is a front view of a first embodiment of a display screen with graphical user interface, showing our new design;

FIG. 2 is a front view of a second embodiment of a display screen with graphical user interface, showing our new design; and,

FIG. 3 is a front view of a third embodiment of a display screen with graphical user interface, showing our new design.

The broken line at the periphery of the graphical user interface illustrates the display screen and the remainder of the broken lines illustrate portions of the graphical user interface. None of the broken lines form part of the claimed design.
